MEANS FOR CLASSIFYING MATERIALS

John Malcolm Nicol, Mill Valley, Calif.

Application March 12, 1934, Serial No. 715,068

5 Claims. (Cl. 209—452)

My invention relates to a means for and method of concentrating unclassified materials, and more particularly to devices embodying the methods of my invention for use in placer and dredge mining.

5 My invention more specifically relates to the art of separating and saving, by virtue of the difference in specific gravity, gold, platinum, free metallic particles and associated mineral particles and gems from the worthless light sand and fine 10 gravel with which these products are customarily associated in natural deposits.

Among the objects of my invention are: to provide a method of concentrating unclassified materials; to provide a method of classifying materials having different specific gravities; to provide a rotating riffle; to provide a method of abstracting concentrates from a stream of unclassified material at right angles to the direction of flow of said stream; to provide a means and method 20 for relieving a riffle box of material tending to interfere with the action of the riffles; to provide a new and unique revolving drum sluice box; to provide a revolving drum concentrator wherein concentrated material is continuously and simultaneously removed at right angles to the direction 25 of flow of the material in a circular path; and to provide a novel and efficient sluice box.

Other objects of my invention will be apparent or will be specifically pointed out in the description forming a part of this specification, but I do not limit myself to the embodiment of the invention herein described, as various forms may be adopted within the scope of the claims.

In the drawing attached hereto and forming a 35 part of the specification:

Figure 1 is a side view in elevation of the concentrator and classifier of my invention.

Figure 2 is a perspective view looking into the interior of the revolving drum.

40 Figure 3 is a section of the revolving drum illustrating the action of the device.

To more clearly indicate the scope of my invention, a summary of the present standard methods of saving, as presently practiced in placer mining or dredges, will be helpful.

The sluice box may be said to be the heart of all present devices, and no matter what the final form may be, it consists essentially of a trough or box set at some predetermined grade and lined 50 along the bottom with some form of riffle. The riffles are usually transverse to the line of flow of the stream of material passing through the device. The material from which it is desired to concentrate certain portions, is passed through 55 the sluice box, usually mixed with a relatively

large volume of water, the entire stream having a relatively high velocity.

The function of the riffles is twofold. Firstly, there is an ascending boil or an upward classifying current in front of each riffle contrasted with 5 the nearly horizontal flow of most of the mass of the stream. Secondly, the riffles form a pocket or catchment point for the heavier particles of the stream which are sufficient in weight to settle downwardly against the classifying current of the 10 boil.

Practically all forms of present apparatus, pans, rockers, long toms, slices, sand tables and innumerable other similar devices used in placer mining are based on this fundamental principle, 15 and attempt to make a one stage operation of the removal of metallic particles from the gravels. By "one stage operation" it is meant that the classification, as-far-as the concentrates are concerned, is supposed to be complete or nearly so. 20 In other words, the concentrates are supposed to contain almost all of the materials sought for and not a great deal of anything else. It is my opinion, however, that the method as outlined is subject to certain grave defects.

In the ordinary embodiment of such sluices, the separating action is usually continuous whereas the cleaning of the riffles is intermittent, and in many cases, due to the time lost in cleaning up the concentrates, that step is left until the last possible moment. 30 In fact it is quite customary in sluice box installations to have the riffle bars extend over a much longer length of stream than is at first necessary when the box is clean, and as the riffle bars get filled up with deposits and fail to operate, other 35 bars further down the line swing into operation.

In many other commercial installations new riffle bars are added as prior ones fill up, and the process extended for as long a time as desirable. Furthermore, due to the long intervals between 40 clean-up shut downs, it is necessary to change various other conditions as, for example, the height of the riffles, steepness of the grade, violence of the boil or like conditions surrounding the sluice. Many times the increase of velocity 45 of the stream or classifying currents will boil-out material from prior filled riffles, and consequently a great deal of associated fine, flaky, or spongy gold is completely washed over the riffle line and lost.

These conditions are greatly aggravated 50 in those placer installations where the proportion of heavy black sands and other concentratable materials is abundant. A great deal of trouble has been encountered along these lines in tin placer installations, as a concrete example. 55

A careful examination of the defects in placers brings to light the fact that multiple stage operation is desirable, that is, to save in one crude or rough concentrating operation everything that 5 is heavy, including black sand or similar materials, and subsequently, by more refined methods, to separate out the metallic particles from the associated heavy minerals. Many of the associated minerals have been shown to contain included valuable metals and other desirable by- 10 products. Furthermore, for efficient operation I have found that the riffles should be continuously cleaned or discharged while in operation, and one step in my method, in its broadest aspect, comprises removing the concentrates from a sluice 15 box continuously in a direction approximately at right angles to the flow of the material. I realize that this particular step has long been recognized as fundamental in the best concentrating devices, such as the "Wilfly" table, various vibrating jigs and like apparatus. My invention goes further, however, and not only provides for the removal of the concentrate continuously in a direction at approximately right angles to 20 the direction of flow of the material, but also includes the steps of raising the material out of the stream and dumping it, by gravity, into a collector. A still further step may be desirable in case the unclassified material contains relatively 25 coarse material too large and heavy either to be removed during the cleaning operation or to boil over the riffles. Such material is exemplified by certain rounded boulders or slate slabs. It is obvious that such large units, lodging against the 30 riffles, will alter the riffle currents and impair the efficient operation thereof.

The apparatus embodying my methods, in broad terms, therefore, will include a rotating drum type of concentrator wherein parallel 40 transverse ring riffles are positioned, means for passing the unclassified material through the concentrator, and longitudinal riffles between the various transverse riffles to catch the concentrates, remove them at right angles to the flow 45 of material, and as they rotate around the axis of the drum, I provide means for catching or collecting the raised material as it is dumped under the influence of gravity. In many cases where the concentrated material is adherent I may prefer 50 to aid gravity by the use of water streams so that the washing action thereof will aid gravity in relieving the longitudinal riffles of their concentrates. Furthermore, in case there are in the unclassified material, boulders, slate or other 55 materials which are liable to jam against the transverse riffles, and which are not easily removed therefrom by the moving longitudinal riffles or the force of the stream, I provide short gaps in my transverse riffles, preferably staggered 60 in relation to each other, and in many cases it may be desirable to provide means between the transverse riffles for urging such interfering material toward the gaps. I thereby provide a complete path through the drum and 65 the interfering materials quickly pass through.

My invention, in both of its aspects, may be more readily understood by reference to the figures which illustrate a preferred embodiment of my invention, adapted to concentrate gold bearing materials from placer deposits. As the embodiment illustrated is of a semi-portable type, I prefer to mount the device on a foundation frame 1. Bearing brackets 2 are positioned at one end of this frame, and a drum frame 3 is attached thereto by means of pivots 4. The other

end of the foundation frame is provided with a screw plate 5 adapted to receive the end of an adjusting screw 6 threaded in the drum frame 3. When the foundation frame 1 is placed upon the earth the grade of the device may be determined or changed by rotating the adjusting screw 6. Flanged rollers 7, mounted on the drum frame 3 by means of roller brackets 8, support a rotating drum 9 through the medium of bearings rings 10. The flanges on the rollers 7 maintain the drum 10 in place even though the angle or grade of the drum may be considerable.

The drum is rotated through the medium of a power shaft 11, terminating in a pinion gear 12, engaging a circumferential master gear 14 on the drum. Other suitable means of rotating the drum may obviously be applied thereto. A feed chute 15 is positioned at the higher end of the device and is adapted to feed unclassified material into the interior of the drum, and an output chute 16 is positioned at the other end, adapted to carry away the discharge waste from the drum.

The construction of the interior of the drum is shown in Figures 2 and 3. A series of parallel, circumferential, cross riffles 17 are secured to the interior of the drum wall, projecting inwardly. I prefer to equally space these cross riffles along the drum. The height of the cross riffles will, of course, be dependent upon various factors, such as the amount of water available in the incoming material, the type of incoming material, and the specific gravities existing in various particles of the material. Between the cross riffles and between the end cross riffles and the end of the drum are positioned longitudinal riffles 18. These riffles may either be fastened to the cross riffles 17 or to the inner wall of the drum. I prefer, however, to line the interior of the drum underneath the riffles with corrugated rubber matting 19 and so arrange this matting that the corrugations 20 thereof shall extend longitudinally of the drum and be parallel in extent with the longitudinal riffles. I also prefer to make the longitudinal riffles of lesser height, that is, extending inwardly to a lesser extent than the cross riffles and to make the corrugations in the rubber matting substantially of lesser radial extent than the longitudinal riffles.

A stationary interior launder 21 in the form of a partition, longitudinally bisects the interior of the drum. While this launder may have variations in shape consistent with the operation thereof, I prefer to make the device slightly concave in order to assist received material to run to one end thereof where it may be led into a concentrate chute 22, the material being delivered thereby into a suitable concentrate receptacle 23. I prefer to support this launder on launder brackets 24 fastened to the drum frame. If desired, the discharge angle of the launder may be made variable.

It is usually desirable to turn up the lateral edges 25 of the launder and also to provide them with indentations 26 wherein the cross riffles 17 may rotate, thus allowing the lateral edges of the launder to closely approach the inner edges of the longitudinal riffles 18.

I also prefer to leave gaps 27 in each of the cross riffles 17 and to so stagger these gaps that there will be a complete, preferably spiral, path along the entire drum through which certain objectionable material may be passed, as will be described later; and I may desire, in certain cases, to place adjacent each of these gaps an angular bar 28, of substantially the same height as the

longitudinal riffles, positioned to direct such objectionable material through the gaps and thus eventually to cause it to pass from the machine.

In operation, unclassified material, prefer-

ably mixed with a suitable amount of water, is continuously run into the drum through chute 15, the drum having been set at the proper grade. The drum is, at the same time, slowly revolved, preferably at a speed between two and six R. P. M. 10 The cross riffles 17 act in exactly the same manner, as they revolve, as the usual riffles in the ordinary sluice box, causing heavy materials to be deposited. Such materials, being in between the longitudinal riffles, are continuously carried 15 away during the rotation of the drum, and furthermore, at the same time, are carried upwardly and out of the stream of mixed water and material.

I have shown in the drawing that the longitudinal riffles 18 are provided with a retaining lip 29. This lip, however, which makes the riffles somewhat the equivalent of a bucket, is not always necessary and its presence will depend, to a large extent, on the packing and settling 20 qualities of the concentrates.

As the loaded longitudinal riffles pass upward past the lateral edges of the launder, they are tipped, due to their radial positioning, toward the launder, and at some point as they pass over the 30 launder they will discharge their contents, which, in falling, will be intercepted by the launder. In order to aid the discharge of material from the launder, I may desire to supply liquid, preferably water, through a suitable pipe 30, generally 35 centrally located above the launder, which has washing jets 31 positioned to direct streams of water over the surface of the launder, loosening the concentrates and washing them into the discharge chute 22. It may also be advisable to clean 40 the longitudinal riffles, and I may therefore provide a cleaning nozzle 32 positioned to direct a stream of water against the longitudinal riffles after they have reached a position above the launder. Such a stream tends to loosen packed 45 fines and aids gravity in the discharge of the material carried by the longitudinal riffles. It may also be desirable to direct a relatively gentle stream of water against the longitudinal riffles by means of a settling pipe 33 having a settling jet 50 34 adapted to direct a gentle flow only of water between the longitudinal riffles before they come to a position above the launder. The object of 55 this gentle washing is simply to clean out the small corrugations between the longitudinal riffles, and deposit all of the concentrates against the upper face of the rising longitudinal riffles, from which they may be readily dumped.

As the entire action is continuous, the cross and longitudinal riffles are freed from their deposits 60 and enter the stream again on the opposite side clean and ready for efficient operation. My device will be completely operable in all respects without the use of the gaps 27, if there are no objectionable materials in the unclassified mass. It 65 many times happens, however, that a boulder, piece of slate, or similar object lodges in front of a cross riffle and is too heavy to be washed over, and too large to be carried out of the stream by any of the longitudinal riffles. This means, then, that the riffling action would be destroyed, 70 as far as that particular riffle is concerned, and if by any chance several of these obstacles should come along in the stream, pass over one or more of the riffles but not all, it is conceivable that all 75 the cross riffles might, in the course of time, be-

come damaged in their action and necessitate a shut-down. I have therefore provided for the elimination of these obstacles by the use of the gaps 27.

As the drum rotates there will come a time 5 when a gap is immediately in front of the objectionable object, and the object will usually be forced through the gap by the stream to land against the next, riffle. As the drum rotates, however, the next gap immediately presents itself 10 to the obstacle; it passes therethrough, and so on through the entire drum until the obstacle passes completely out of the drum into the output chute. At the same time, by having the gaps staggered, I prevent the loss of valuable 15 concentrates when the gap in one riffle is centered with respect to the stream, as the other gaps are either off center or out of the stream entirely. Yet within a short period of revolution, determined by the amount of gap offset, the obstructive material is completely passed along and 20 through the drum.

It sometimes happens, however, that the obstacle is of such angular shape that it is not pushed by the force of the stream through the 25 gaps but normally tends to stop before it reaches a cross riffle. I have, therefore, to take care of such obstacles, positioned the angular bar 28 in front of each gap so that a blow may be struck 30 to the obstructive material at least once every revolution, this blow being angularly applied and urging the obstacle toward the adjacent gap. I have found in practical operation that tramp iron, boulders, regularly shaped blocks such as 35 bricks, or irregular shaped angular masses such as cracked boulders having a flat side tending to stabilize them in a certain position, are passed through the device with a minimum of disturbance of the riffling action.

It will be seen, therefore, that my concentrator 40 is continuous in the true sense of the word in its action. There are no shut-downs for clean ups. A rough concentration is continuously performed and material which will tend to obstruct the action of the riffle is continuously acted 45 upon to pass it through the device with a minimum of disturbance of the action thereof. The concentrates collected in the receptacle 23 may be further treated in any convenient manner to recover the values therefrom, and fines in the 50 form of flake gold, for example, are not lost during the sluicing process.

It is obvious, of course, that the mounting of the device may be varied to suit conditions, within the scope of the claims. 55

I claim:

1. In apparatus for classifying materials, a rotating cylindrical vessel, means for passing an unclassified material through said vessel, a plurality of parallel circumferential cross riffles arranged transversely within said vessel, longitudinal riffles extending between said cross riffles of lesser height than said cross riffles, means for collecting the material carried by said longitudinal riffles, and means for preventing accumulation 60 in front of said cross riffles of interfering material too large to be carried by said longitudinal riffles and too heavy to be forced over said cross riffles by the pressure of the unclassified material. 65

2. In apparatus for classifying materials, a rotating cylindrical vessel, means for passing an unclassified material through said vessel, a plurality of parallel circumferential cross riffles arranged transversely within said vessel, longitudi- 70

nal riffles extending between said cross riffles of lesser height than said cross riffles, said cross riffles each having a gap therein for passage of interfering material too large to be carried by 5 said longitudinal riffles and too heavy to be forced over said cross riffles by the pressure of the unclassified material.

3. In apparatus for classifying materials, a rotating cylindrical vessel, means for passing an 10 unclassified material through said vessel, a plurality of parallel circumferential cross riffles arranged transversely within said vessel, longitudinal riffles extending between said cross riffles of lesser height than said cross riffles, said cross 15 riffles each having a gap therein for passage of interfering material too large to be carried by said longitudinal riffles and too heavy to be forced over said cross riffles by the pressure of the unclassified material, the gaps in the cross riffles 20 being staggered each from the preceding to form a spiral path for said interfering material through said vessel.

4. In apparatus for classifying materials, a rotating cylindrical vessel, means for passing an 25 unclassified material through said vessel, a plurality of parallel circumferential cross riffles arranged transversely within said vessel, longitudi-

nal riffles extending between said cross riffles of lesser height than said cross riffles, said cross riffles each having a gap therein for passage of interfering material too large to be carried by said longitudinal riffles and too heavy to be forced over 5 said cross riffles by the pressure of the unclassified material, and means positioned between said cross riffles to urge said interfering material toward said gaps during the rotation of said vessel.

5. In apparatus for classifying materials, a ro- 10 tating cylindrical vessel, means for passing an unclassified material through said vessel, a plurality of parallel circumferential cross riffles arranged transversely within said vessel, longitudi- 15 nal riffles extending between said cross riffles of lesser height than said cross riffles, said cross riffles each having a gap therein for passage of interfering material too large to be carried by said longitudinal riffles and too heavy to be forced over said cross riffles by the pressure of the un- 20 classified material, and a diversion bar positioned between said cross riffles to urge said interfering material toward each of said gaps during the rotation of said vessel, said diversion bars being of a height not greater than that of the longitudi- 25 nal riffles.

JOHN MALCOLM NICOL.
